UNITED STATES PATENT OFFICE.

EDWARD G. GERMER, OF ERIE, PENNSYLVANIA.

DESIGN FOR A STOVE.

SPECIFICATION forming part of Design No. 30,908, dated May 30, 1899.

Application filed May 6, 1899. Serial No. 715,869. Term of patent 7 years.

To all whom it may concern:

Be it known that I, EDWARD G. GERMER, a citizen of the United States, residing at Erie, in the county of Erie and State of Pennsylvania, have invented a certain new and original Design for Stoves; and I do hereby declare the following to be a full, clear, and exact description of the invention, such as will enable others skilled in the art to which it appertains to make and use the same, reference being had to the accompanying drawing, and to the letters of reference marked thereon, forming part of this specification.

The leading features of my design consist, substantially, in the form and ornamentation of a heating-stove which embodies a base circular in its general contour and ornamented with raised scrollwork, which base is mounted upon ornamented legs in the usual manner. Upon this base there is mounted a cylindrical stove-body having an ornamented stove-door frame and door near the base thereof and an open ornamented scrollwork sloping downward and outward from the lower part of the stove-body, to which is secured a plain foot-rail. On the front of the stove-body, above the door, there is a rectangular name-plate having a scrollwork border, and on the top of the stove-body there is a top, generally conical in shape, ornamented with scrollwork and surmounted at its apex by an ornamented urn.

The figure shows a perspective view of a heating-stove embodying my design.

In the drawing, A is the base of the stove, which is circular in shape and slopes upward and inward from the bottom thereof toward the stove-body B. The base A is mounted upon four legs C equidistant from each other, which are ornamented by means of raised scroll and foliate work c c'. Between the legs C the lower edge of the base A curves downward and is ornamented by raised scrollwork A', portions of which extend around above the legs C.

The stove-body consists of a plain upright cylinder B, having an annular bead b thereon. On the front of the stove-body B, near

the bottom thereof, there is secured a rectangular door-frame D, ornamented with raised scrollwork d, and in this frame there is a door D', having an ornamented border of scrollwork d' and a central circular panel d'', surmounted with an octagon-shaped damper E, ornamented with scrollwork e and provided with a transverse handle e'. Commencing at each side of the door-frame D there is an ornamental scrollwork F, which slopes downward and outward from the stove-body B and is provided with projections f, upon which is secured a plain circular foot-rail G, which overhangs the upper part of the base A.

Above the door-frame D there is secured to the stove-body B a rectangular name-plate H, having an ornamental border of raised scrollwork h and a central ornamental figure h'. Upon the top of the stove-body B there is a stove-top I, the edge of which consists of a plain oval band I', overhanging the stove-body B, and above this band I' the stove-top curves inward and upward to the base of the apex-section J and is ornamented by raised scrollwork I''. The apex-section J is of a general semiglobular shape and has a plain band J' around the base thereof, above which it consists of open scrollwork J''. Upon the apex of the section J there is mounted an urn K, the base K' of which consists of open scrollwork and the body thereof of open scrollwork k, with a central star-shaped figure k' in a circle, and at the sides of the body of the urn are handles L of open scrollwork, while the top M of the urn is semiglobular, ornamented with raised scrollwork m, and surmounted by an ornamental knob m'.

Having thus described my new and improved design, what I claim is—

The design for a heating-stove, substantially as herein shown and described.

In testimony whereof I affix my signature in presence of two witnesses.

EDWARD G. GERMER.
